UNITED STATES PATENT OFFICE

GEORGE H. DAWSON, OF CAMBRIDGE, MASSACHUSETTS, ASSIGNOR, BY MESNE ASSIGNMENTS, TO REMINGTON RAND INC., OF NEW YORK, N. Y., A CORPORATION OF DELAWARE

OVERLAPPING VISIBLE INDEX

Application filed July 10, 1925. Serial No. 42,727.

This invention relates to a visible index in which cards are supported in overlapping relation to provide exposed margins.

It is among the objects of this invention to provide such an index in which the card supports are articulated one to the other and in which any support may be removed from the others and a new one substituted therefor or in which a section of the index may be removed as a unit or replaced.

With these and other objects in view which will become more apparent in the following description and disclosures, this invention comprises the novel structure and combinations hereinafter described and more particularly pointed out and defined in the appended claims.

In the accompanying drawings, which illustrate certain preferred embodiments of this invention and in which similar reference numerals refer to similar features in the different views:

Figure 1 is a front elevational view of an overlapping visible index involving this invention;

Figure 2 is an enlarged elevational view of a detached support with a card removably mounted thereon;

Figure 3 is an enlarged sectional view upon the line III-III of Figure 2;

Figure 4 is an elevational view of the index involving a slight modification in the manner of attaching the cards to their supports;

Figure 5 is an elevational view of a single support with an attached card detached from said index; and

Figure 6 is a sectional view upon the line VI-VI of Figure 5.

Figure 7 is a view illustrating one end portion of a pair of supports showing the manner in which the supports are interconnected in the reversed position to that which is illustrated in Figure 4, whereby a greater visible margin of each record card is obtained.

As shown on the drawings:

As illustrative of this invention, there is shown an index comprising a series of articulated supports to which cards are attached and from which they are suspended. In Figures 1 to 3 the cards are detachably secured to the supports while in Figures 4 to 6 the cards are permanently attached to their supports.

Each support consists of a flexible strip 1 which is preferably made of thin cardboard or the like. In the lateral edges of each supports are substantially V-shaped clefts which are respectively spaced a suitable distance from the horizontal edges of the support to provide attaching means or articulating tongues 2 and 3 either of which may be used for articulating purposes. Triangular apertures 4 are provided near the lateral margins of the supports. The base of each triangular aperture lies in a transverse or vertical plane; and the apices are directed toward the lateral margins or ends of the support and the distance between the outer apices of the apertures corresponds to the distance between the V-shaped clefts to form receiving means for said clefts.

In the present instance, the apertures 4 are offset from the longitudinal center line of each support. As shown, the apertures 4 are nearer to the upper edge of the support than to the lower edge and the cards are suspended from the upper edge. The exposed margin on each card will substantially correspond to the distance between the upper edge of the support and the aperture. If the supports are used in inverted position that is, upside down, to support the cards, this distance becomes greater so that a larger margin of the cards becomes exposed.

The manner of attaching the cards upon these supports will now be described. In Figures 1 to 3, each support has a heavy paper hinge 5 attached thereto. The paper hinge preferably has a portion folded over

the upper edge of each support and glued or attached to the rear of the support as indicated at 6 in Figure 3. Suitable weakening apertures 7 may be made in each hinge member adjacent the upper edge of each support to increase the flexibility. Hence the paper hinge that depends upon the front side of each support is free to swing upwardly into a substantially vertical plane for exposing 10 the card therebeneath.

Each paper hinge has a pair of eyelets 8 which are suitably spaced to receive the notches 9 in the lateral edges of the cards 10. Each eyelet has a disk 11 upon its front 15 end for retaining the card. The cards 10 are placed upon the retaining eyelets or studs by flexing as is well known in the art. Each card may readily be removed from its support by a similar flexing movement.

20 In Figures 4 to 6, each card 10^a has an integral portion 12 folded over the upper edge of each support and glued or secured to the back thereof whereby each card is permanently attached to its support.

25 In assembling the index, it is preferable to begin with the uppermost index card or hinge and its support and articulate the second support with its attached card or hinge to the first support; the first card may 30 readily be swung upwardly for such a purpose. The third support may then be articulated to the second support and so on. It is hence apparent that index cards may be added as needed.

35 If desired the card or sheet supports may be inverted to vary the exposed margins. In such case the cards or sheets will hang suspended from the lower edges of their supports. Instead of attaching the cards or sheets to the upper margins of the supports 40 they may be attached to the lower margin.

It will be noted that each support overlaps the adjacent support; likewise each nether card has an exposed margin with respect to 45 the overlying card. Further, a section consisting of a plurality of supports and their cards may readily be removed or replaced as a unit. With respect to the structure shown in Figure 1, the cards are also removable 50 from their supports. In the assembled index, it should also be noted that the attached margin 6 of the card hinge in Figure 3 and the attached portion 12 of the card in Figure 6 will be between two supports 1, which not only obscures the same but also tends to 55 maintain the same secured.

I am aware that many changes may be made and numerous details of construction may be varied through a wide range without departing from the principles of this invention, and I therefore do not purpose limiting the patent granted hereon, otherwise than necessitated by the prior art.

I claim as my invention:

65 1. In an index device, a series of similar

strips superposed on one another with their edges in offset relation so as to form a series or chain of strips, interlocking means for detachably maintaining said strips in chain form, and a series of record cards, each having means hingedly connecting one edge to one marginal portion of one of said strips, said strips supporting said series of cards with a free marginal portion of each card exposed in visible index relation.

70 2. In an index device, a series of similar strips superposed on one another with their edges in offset relation so as to form a series or chain of strips, interlocking means for detachably maintaining said strips in chain form, and a series of record cards having means hingedly connecting, one to each strip, 75 in overlapping relation, said strips holding said record cards with a free marginal portion of each in visible index relation.

80 3. In an index device, a series of similar strips superposed on one another with their edges in offset relation so as to form a series or chain of strips, interlocking means for detachably maintaining said strips in chain form, a series of record cards, and means 85 detachably and hingedly supporting said cards in overlapping relation, one on each strip, with a free marginal portion of each card in visible index relation.

90 4. In an index device, a series of similar strips superposed on one another with their edges in offset relation so as to form a series or chain of strips, interlocking means for detachably maintaining said strips in chain form, a series of record cards, and holder members, one holder member being hingedly connected to each of said strips, and said members having means for detachably holding said record cards in overlapping relation 95 with a free marginal portion of each card in visible index relation.

100 5. In an index device, a series of similar strips superposed on one another with their edges in offset relation so as to form a series or chain of strips, interlocking means for detachably maintaining said strips in chain form, a series of record cards, a series of card holders, each card holder having means 105 providing a hinge connection to one strip, and means for detachably connecting each record card to one card holder, said series of cards having a free marginal portion of each card arranged in visible index relation.

110 6. In an index device, a series of similar strips superposed on one another with their edges in offset relation so as to form a series or chain of strips, interlocking means for detachably maintaining said strips in chain form, and a series of record cards, each card having a marginal portion provided with means hingedly connecting it to a marginal portion of one of said strips and supported in said index in overlapping relation with 115 120 125 130

a free marginal portion of said card in visible index relation.

7. In an index device, a strip having interlocking means on opposite marginal portions and cooperating means intermediate said marginal portions unequally spaced from each of said marginal portions, said interlocking means being independently adapted to detachably interlock with the cooperating means on a similar strip to form a series or chain of strips with overlapping edges in visible index relation, one of said interlocking means supporting said strips with a wider visible margin than the other, and 15 a record card on each strip, each record card having a marginal portion secured to its respective strip.

In testimony whereof I have hereunto subscribed my name.

20 GEORGE H. DAWSON.
